(Cl. 122—1)

This invention relates to steam generating systems and apparatus adapted for the generation of steam at high pressures as around six hundred pounds per square inch and correspondingly high temperatures.

The steam generating system and apparatus of the present invention is particularly adapted for locomotive and marine service where high power capacity must be obtained from apparatus of restricted dimensions, although the invention has valuable features other than compactness that render the system and apparatus desirable for other types of service.

There are two general types of boilers, the fire tube boiler wherein combustion gases pass through tubes surrounded by water, and the water tube boiler wherein the combustion gases circulate about water-containing tubes. A fire tube boiler is not practicable, however, for the 10 direct generation of steam at pressures approximating six hundred pounds per square inch for the purposes of this invention because of the relatively great thickness of the boiler shell and associated parts rendered necessary by the high pressures. A water tube boiler, however, while well adapted for high pressure steam generation occupies an objectionable amount of space for the present purposes because of the necessity for a large furnace and large combustion gas 20 ducts. Furthermore, the furnace requires a heat insulating lining which will not stand up when subjected to vibrations such as it would occur especially in locomotive use. The present invention also comprehends a control of the steam generating system that extinguishes or reduces the fire when steam is not required to be made. A boiler having a heat insulating lining in the combustion space is not susceptible to such control since the heat stored in the heat insulating 30 lining would continue to give off heat for a considerable period of time after the fire had been extinguished or reduced, thereby nullifying the intended effect of the fire control.

Hence an object of the present invention is the provision of a fuel burning, steam generating system including a novel type of steam generator that is capable of generating large amounts of steam at high pressures and yet is compact, has only small diameter parts that are subjected 40 to the high pressure so that the parts can be relatively thin and yet light and has a fire box or furnace that does not necessitate a heat insulating lining.

A further objection to the use of a boiler of the ordinary type for generating steam at high pressure is the considerable danger of failure of a high pressure carrying tube or shell due to pitting, corrosion, or scale formation when subjected to the hot furnace gases.

60 The Scotch type of boiler needs no heat in-

sulating lining for its internally located fire box and is capable of high output capacity for its volume but by reason of its design is suited only to low pressures. It is an object of the present invention to utilize this type of boiler for the 5 generation of high pressure steam by the use in the boiler of an intermediate liquid having a high vapor temperature for a low vapor pressure, and using the vapor of the intermediate liquid for the generation of high pressure steam. Thus 10 the inherent advantages of the internal fire box type of boiler are utilized within the vapor pressures for which it is suited.

While steam can be made by piping a high temperature low pressure intermediate vapor 15 generated in a low pressure boiler through a heat exchanger and generating high pressure steam in the tubes of the exchanger and piping the intermediate vapor condensate back to the boiler, such a system does not have the volume efficiency, that is to say, the high ratio of power output as compared to the volume occupied, 20 that is required for the purposes of this invention.

Furthermore, the use of an intermediate liquid 25 boiler, a heat exchanger, and the piping necessary to connect the two, not only increases the space required of the system but introduces piping that must be very large to accommodate the large flow of intermediate vapor required for a 30 large steam power output but further may introduce complications in the way of getting the intermediate liquid vapor to the exchanger and the condensate back into the boiler.

It is an object of the present invention to provide means to generate vapor from the intermediate liquid and high pressure steam from the vapor in such a way as greatly to reduce the space required of the system and the amount of intermediate liquid, and also to greatly simplify 40 the exchange of heat from the intermediate liquid vapor to the steam.

In carrying out the above results the intermediate liquid boiler and the heat exchanger are constructed as a single unitary structure wherein 45 the water and steam pipes of the exchanger, in which the high pressure steam is generated, are located directly in the vapor space of the intermediate liquid boiler so that not only is the space heretofore required for the exchanger 50 eliminated but the piping between the boiler and exchanger are also eliminated with the consequent elimination of any problems connected with conducting the intermediate liquid vapor to the exchanger and the condensate back into the 55 boiler. Such an arrangement constitutes an important object of the present invention.

A further object of the invention is a boiler arranged as above described, the boiler consisting of large and small drums or shells, prefer- 60

ably cylindrical, arranged one on top of the other and having communicating open sides admitting free vapor communication between them, with the edges of the shells at the openings secured together at points lying in a plane perpendicular to the plane including their axes and tied together by tie members traversing the openings; the small shell containing the steam generating tubes and the large shell containing the intermediate liquid. Such a construction is inherently strong and compact.

A further object of the invention is the provision of a two-drum boiler constructed as above described having parallel external ducts for the combustion gases located on opposite sides of the small drum and containing water tubes and constituting economizers in which the water is heated prior to passing to the exchanger.

It is also an object of the invention to provide the intermediate liquid boiler with fire tubes containing superheater tubes and to arrange the boiler, economizer heat exchanger and superheater so that the tubes of the economizer, exchanger and superheater can be withdrawn all from the same end of the boiler.

A further object is the provision of a steam generating system particularly adapted to sudden variable demands, as in locomotive service, and wherein the generation of steam is practically immediately responsive to the steam demand so that steam generation ceases immediately when the steam demand ceases, or the throttle is closed, and steam is immediately made when there is a demand for steam, as when the throttle is opened.

A yet further object is the provision of a steam generating system wherein steam is generated by a heated intermediate fluid having a relatively large heat storage capacity which is utilized to generate steam immediately in response to steam demand and irrespective of any time lag between the initiation of steam demand and the heating of the intermediate fluid.

It is another object of the invention to provide a closed cycle steam generating and utilizing system having a substantially constant volume of water therein, and a novel control system for the steam generating system which includes means providing for the introduction of water into different parts of the steam system automatically in response to a predetermined steam pressure and also in response to a predetermined water level in a water storage or hot well.

A yet further object is the provision of a control system for the steam generating system wherein water is introduced into the high pressure steam between the heat exchanger and the superheater under control of the steam pressure for the purpose of maintaining a constant steam pressure under certain conditions of operation of the system.

A further object is generally to improve upon high pressure steam generating systems and apparatus.

Fig. 1 is a sectional elevation taken through the longitudinal axis of the steam generator forming a part of the present invention.

Fig. 2 is a front end view of the steam generator of Fig. 1, one-half of the view being a section taken along line 2—2 of Fig. 1.

Fig. 3 is a sectional detail taken along line 3—3 of Fig. 1 and illustrating in cross-section the super-heater header and the economizers.

Fig. 4 is an end detail of the upper back end of the boiler.

Fig. 5 is a view of the inner face of the heat exchanger cover plate, looking in the direction of line 5—5 of Fig. 1, and illustrating particularly the partitions between the various groups of tubes in the heat exchanger.

Fig. 6 is an enlarged sectional detail of an economizer header.

Fig. 7 is a diagrammatic view of the steam generating and control system.

Fig. 8 is a sectional detail of the float controlled valve regulating the flow of water through the system.

Fig. 9 is a sectional detail of the oil throttle valve of Fig. 7.

Fig. 10 is a sectional detail of the separator-pressure controlling valve of Fig. 7.

The steam generator comprising a part of the present invention is illustrated in Fig. 1. It comprises a cylindrical outer shell 12 having front and back heads 14 and 16, respectively. The boiler is of the Scotch marine type and has an internal fire box or combustion chamber extended substantially the entire length of the boiler and comprised of the cylindrical corrugated shell 18, the front head 20 to which the front end of the shell 18 is secured, the intermediate head 22 to which the rear end of the shell is connected, and the back head 24 which is connected to the intermediate head 22 by a cylindrical plate 26. The front head 20 of the fire box and the front head 14 of the boiler are conveniently provided with aligned apertures 28 surrounded by connected flanges 29, through which apertures fuel is introduced into the fire box. In practice the heads 20 and 14 and 22 and 16 will be stayed together in the usual manner not necessary to illustrate herein. A plurality of fire tubes 30 extend from the intermediate fire box head 22 above and parallel with the fire box shell and through the front boiler head 14 and are disposed arcuately about the upper part of the fire box.

In accordance with this invention water-carrying steam-generating tubes are disposed within the boiler above the intermediate liquid level and in direct contact with the vapor therein. Since, however, provision for the tubes inside the shell 12 of the boiler would result in an undesirable enlargement of the diameter of the shell and also require a stronger shell, the tubes are disposed in a secondary boiler shell 32 which is disposed on top of and parallel with the shell 12 and is substantially the length of said shell and is open for free communication therewith through substantially its entire length. To this end the top portion of the shell 12 is provided at its top with an opening 34 that extends substantially the length of the shell, or the ends 36, see also Fig. 2, of the shell sheets are spaced apart to provide the opening. The ends 36 are also shaped to lie in a horizontal plane. The shell 32 of the heat exchanger is similarly constructed or is provided with a longitudinally directed opening 38 between the spaced ends 40 of the shell sheets thereof, the opening extending substantially the length of the shell. The ends 40 are similarly flattened into a horizontal plane. A tie plate 42 is disposed between the flattened ends 36 and 40 of the two shells and the ends of the sheets of the two shells are secured to said tie plate in a fluid tight manner by welding or otherwise. The plate 42 is provided with a longitudinal series of large openings 44 with interposed tie sections 46 which connect and tie together the ends of the shell sheets on opposite sides of the openings. This arrangement of uniting the shells together is simple and

entirely practicable since it has been found that the resultant stresses between the shells lie in the plane of the plate 42. The openings 44 permit free circulation of the vapor of the intermediate liquid and the condensate thereof between the two shells.

The back end of the shell 32 is closed by the head 48 and the front end is removably closed by a head 50 in which are expanded or otherwise secured the ends of a plurality of groups of heat exchanger tubes 52, the open ends of the tubes being surrounded by a continuous housing flange 54, the open end of which is closed removably by a cover 56 having an inlet passage 58 for water and an outlet passage 60 for steam. The housing 54 and its cover 56 are provided with registering partition walls. Said walls consist of a vertical partition 62, an upper horizontal partition 64 and a lower horizontal partition 66, the partitions being joined together and to the housing to form between them chambers permitting fluid flow in series between the various groups of heat exchanger tubes. The arrangement is such that water flows through the inlet 58 into the chamber 67a and into the left hand open ends of the top-most group 52a of tubes, see Fig. 2, and through these tubes to the back of the boiler, and thence through the return bends and forwardly to the interior of the chamber and into the chamber 67b and from said chamber into the open right hand ends of the next lower group 52b of tubes and through these tubes and into the chamber 67c and thence into the left hand end of the lowermost group of tubes 52c and through these tubes and into the chamber 67d and into the outlet passage 60. The cross-sectional area of the steam passage through the heat exchanger is progressively increased from the inlet to the outlet by increasing the number of tubes in the groups to accommodate the increase of volume of the fluid approximately in proportion as it becomes converted from water to steam.

The groups of heat exchanger tubes 52 with the front head 50 can be removed as a unit from the shell 32 when desired, the tubes being supported in a suitable conventional manner on tracks 68.

The level of the intermediate liquid in the boiler is at some location above the top of the fire tubes 30 and the smoke box shell 26 but preferably below the plate 42 or at least below the heat exchanger tubes 52. The heat exchanger tubes are thus immersed directly in the intermediate fluid vapor of the boiler and the vapor has free access to the tubes. Any suitable intermediate liquid may be employed that has a sufficiently low vapor pressure at the temperature desired to generate the required steam pressure.

The present boiler is designed to generate steam at six hundred pounds pressure and the intermediate liquid selected for the purpose is one having a vapor pressure of around thirty pounds per square inch and at this pressure having a vapor temperature of around 600° F. This temperature is satisfactory for generating steam at six hundred pounds per square inch. The low vapor pressure of the intermediate liquid permits the use of the Scotch type of boiler herein illustrated with a very light and yet perfectly safe construction. The particular intermediate liquid selected for the purpose is diphenyloxide which is stable at the temperatures employed and is relatively inexpensive in comparison with other mediums having approximately the same vapor temperature and pressure.

The fire tubes 30 of the boiler are occupied by looped superheater tubes 70 of any suitable or desirable construction and arrangement. The ends 72 and 74 of the tubes are connected with a superheater header 76 which is approximately semi-circular in front elevation and is secured to the front boiler head 14 above and partly surrounds the furnace entrance 28. The superheater header is provided with two steam chambers 78 and 80, the chambers being disposed one behind the other and one of the chambers, as the chamber 78, receiving superheated steam from the superheater tubes and the other chamber 80 receiving steam from the heat exchanger. Similar outer ends 72 of the superheater coils are connected with the chamber 78 and the similar inner ends 74 of the superheater coils are connected with the chamber 80. Since the fire tubes 30 are arranged in arcuate lines having a common center which is also the center for the arcuate superheater header, but one type of superheater unit is needed for installation in any one of all the fire tubes.

Steam from the heat exchanger is not passed directly into the superheater header but is passed first into the interior of a separator drum 82, the steam outlet 60 of the heat exchanger being connected with a pipe 84 which extends into the drum 82. Another pipe 86 conducts steam from the separator to the steam inlet 88 of the saturated steam chamber 78 of the header, the inlet 78 being located at one end of the header. The outlet 90 for the superheated steam from the chamber 80 is located at the other end of the header. The separator 82 is adapted at times to receive water to be evaporated by the steam therein for the purpose of controlling the steam pressure, as will be explained in greater detail hereinafter.

The combustion gases from the fire tubes 30 are discharged into an arcuate combustion gas header 92 of which the superheater header 76 constitutes the bottom wall and the front boiler head 14 the rear wall. An arcuate top wall 94 is provided which is suitably secured to the front boiler head and a removable front wall 96 constitutes a closure for the chamber 92, the front wall being removable for the purpose of gaining access to the superheater and fire tubes.

A pair of economizer casings 98 and 100, generally rectangular in cross-section, are disposed above the boiler shell 12 and extend lengthwise thereof on opposite sides of the vapor containing shell 32. The front ends of said casings are in communication with the gas header 92 through ducts 102, of which one is shown in Fig. 2, opening through the top wall 94 of the header. The casings at the back of the boiler communicate with a cross header 104 provided with a stack connection 106.

The economizer casing 98 is occupied by a vertical series of looped water tubes 109 making a plurality of horizontal passes lengthwise of the casings. The economizer casing 100 is provided with a similar series of water tubes 110. The similar ends of all of the tubes of the casing 100 open into a vertical header 112. The other ends of the tubes open into a header 114. The header 112 receives pressure water from a connection 116. Said header, however, has a diaphragm 118 disposed midway between the ends of the collection of tubes 110 connected thereto which blocks off direct passage of the water through the header on opposite sides of the diaphragm. The water is thus constrained to flow from the header 75

into the lower series of tubes below the diaphragm and thence into the header 114 and upwardly in this header into the upper series of tubes and thence from these tubes back into the header 112 above the diaphragm. With this arrangement the series of tubes in the economizer casing 100 are separated into two sets that are connected in series. The water thence passes from the outlet of the header 112 through a cross-over pipe 120 10 into a header 122 similar to the header 112 and associated with the tubes of the economizer casing 98. The water in said header 122 passes in series through the two sets of tubes in said casing, by reason of the diaphragm 124 in said header, and thence out of the outlet 126 of the header 112 into a pipe 128 and thence into the inlet 58 of the heat exchanger.

The connection between the economizer, heat exchanger and superheater is such that the water passes first through the economizer tubes where it receives heat from the partly cooled combustion gases surrounding the tubes and thence passes into the heat exchanger tubes where the water is converted into steam by reason of the high temperature vapor of the intermediate liquid of the boiler. The steam passes from the heat exchanger tubes into the separator 82 and thence through the superheater tubes. The superheated steam passes from the outlet of the tube through 30 a suitable pipe 130 to the prime mover.

The steam generating system and certain of its controls is illustrated diagrammatically in Fig. 7. The boiler is here shown as fired with oil by an oil burner 132 receiving oil from a pipe 134. The operation of the burner is adapted to be controlled by pressure conditions of the vapor of the intermediate fluid. The intermediate fluid boiler 12 is provided with a pressure controlled oil throttle valve 136 which is interposed in the 40 line of the oil pipe 134 and is so arranged, as by the diaphragm 136a and the piston valve 136b (having the oil throttling passage 136c therethrough) that comes up against the end of its cylinder when the intermediate fluid pressure is 45 sufficiently high, that as pressure of the vapor of the intermediate fluid increases above a certain point the supply of oil is gradually diminished and when the vapor pressure reaches a predetermined maximum point the oil supply is diminished to an idling capacity sufficient merely to 50 maintain vapor pressure when no material amount of steam is being made. This method of control serves to maintain a substantially constant intermediate vapor pressure under all conditions of operation and also to prevent the generation of unsafe pressures.

While the burner is herein shown as oil fired the boiler also is particularly adapted for burning powdered fuel by reason of its large combustion 60 chamber.

The system herein shown operates in a closed cycle, all of the steam generated being condensed and the condensate being recirculated to be reconverted into steam. Thus the amount of water 65 in the system is substantially constant and additional water is only required to be introduced infrequently into the system.

The high pressure superheated steam passes from the pipe 130 into the prime mover 138, 70 which may be a turbine or the like. The exhaust steam from the prime mover passes into a condenser 140 where the steam is condensed. Air from the condenser is extracted by an air pump 142. The condensed water is withdrawn from 75 the condenser by a condenser water pump 144

and discharged through a non-return check valve 146 into a hot well 148. Water is withdrawn from the hot well by a continuously operating boiler feed water pump 150 and forced through a pipe 152, a control valve 154 and a pipe 156 into the inlet of the economizer 98, 100. The water thence flows in the manner described above through the heat exchanger 32 where it is converted into steam and thence into the separator 82 and from the separator through the superheater 70. Preferably all the pumps and moving accessory apparatus of the system are electrically operated.

Make-up water when required is introduced into the hot well through a pipe 158. The make-up water preferably is distilled and hence is free from air and scale forming materials. The valve 154 is controlled through a float 160 by the level of water in the hot well. The arrangement is such that the flow of water from the boiler feed pump 160 into the water heating and steam generating sections of the boiler is restricted with low water level in the hot well and permitted with high water level in the well. The movable valve member 162 of the valve, see Fig. 8, is provided with a small passage 164 therethrough or some equivalent arrangement is made whereby a small amount of water is permitted to pass through the system when the valve is closed.

A branch pipe 166 leads from the high pressure outlet of the boiler feed water pump 150 and conducts water through a non-return valve 168 and through a pressure controlled valve 170 to the interior of the separator 82. The pressure controlled valve 170, of which a suitable type is illustrated in Fig. 10, is operated by a bellows 172 or equivalent means supplied with pressure steam through a pipe 174 from the interior of the separator 82. The arrangement is such that when the pressure in the separator is above a certain predetermined value the valve 170 is caused to open to admit water into the separator. The steam in the separator evaporates the water and hence the result is a reduction of pressure of the steam. With a sufficient reduction of pressure the valve 170 closes. Thus the steam pressure is maintained substantially constant.

A small transfer pump 176 may be provided which is adapted to be operated at the time the system is conditioned for operation for the purpose of withdrawing what water there may be in the separator 82 and returning it to the hot well.

A vent line 178 connects the space above the water level in the hot well with the condenser 140.

The operation of the system herein illustrated is essentially as follows:

The hot well is first brought to its full condition of water by the operation of the transfer pump 176 which pump can be stopped after the separator is empty. The oil burner 132 is then started in operation at idling capacity from energy drawn from any suitable outside source as storage batteries. The combustion gases are preferably circulated through the steam generating apparatus by a motor driven exhaust fan 179 which is connected to the combustion gas outlet 106 of Fig. 1. This exhauster is also started in operation at idling speed. In due course of time the oil burner heats up the intermediate fluid in the boiler and causes it to vaporize and to build up a normal operating pressure therein, 70 which pressure will be maintained substantially constant by the operation of the pressure controlled oil valve 136. The boiler feed water pump 150 can then be started in operation. Since the hot well is full of water and the float controlled 75

valve 154 is open the water passes into the heating coils of the generator and steam is generated from the heat of the combustion gases and from the heat of the intermediate liquid vapor. Steam 5 can then be directed into the prime mover to develop load.

The initial circulation of water through the system tends to reduce the vapor pressure within the boiler and thereby increase the amount of fuel 10 fed to the oil burner and burned in the furnace. When the maximum working steam pressure is attained the pressure operated control valve 170 starts to open and admits the relatively cold water from the hot well under pressure of the feed 15 water pump into the separator by-passing the economizer and heat exchanger. Any further increase in steam pressure which will be caused by an increase of vapor pressure in the boiler and exchanger will result in the throttling of the oil 20 supply to the oil burner.

The presence of water in the separator results in a lowering of the steam pressure due to the evaporation of the water by the heat of the steam so that the steam pressure is thereby 25 maintained substantially constant. As the separator steam pressure drops the pressure controlled valve 170 begins to close and closes at a predetermined low pressure. The water from the boiler feed water pump 150 can then re-circulate 30 through the economizer and heat exchanger and again generate steam therein. Intermediate conditions of operation will result in a graduated control tending to hold the separator steam pressure substantially constant. That is to say, when 35 the valve 170 is partly closed a certain amount of water from the boiler feed water pump passes into the economizer and heat exchanger and is converted into steam therein and a certain amount of water passes into the separator and 40 is converted into steam therein. Thus steam is generated in both parts and the operation is such as to hold the steam pressure substantially constant.

The water accumulation in the separator 82 due 45 to the operation of the pressure controlled valve 170, as above described, and also due to any moisture in the steam passing into the separator and settling out therein is automatically compensated for by the float controlled valve 154. Since 50 the amount of water in the steam circulating system is constant any water that is not in the hot well must be in the separator and vice versa. Thus when the hot well is full the separator must be empty, and when the separator has considerable 55 water in it there is a corresponding absence of water from the hot well. With the float controlled valve 154 so arranged that it closes when the level of water in the hot well is low and opens when the level is high steam generation and pressure 60 control is automatically accomplished. For instance, when the level of water in the hot well is at a maximum height there can be no substantial amount of water in the separator and hence steam must be generated by water circulated 65 through the economizer and heat exchanger tubes. When, however, the water level is at its lowest point in the hot well the separator 82 must have its maximum amount of water and hence steam can be generated by the evaporation 70 of the water in the separator. At some intermediate level of water in the hot well the float controlled valve will be partly closed and steam will be generated both by the circulation of water through the economizer and heat exchanger and 75 by the evaporation of the water in the separator.

When the water level is at its lowest in the hot well and the separator has then its maximum amount of water, and since the water therein is required to be converted into steam by the flow of superheated steam into the separator, it is 5 necessary to provide a small by-pass around the float controlled valve 154, which by-pass is conveniently provided by the passage 164 through the movable valve member of the valve. The size of the by-pass is adjusted to admit sufficient water 10 through the economizer and the heat exchanger to vaporize the water in the separator. Since the amount of water circulating through the heat exchanger at this time is relatively small the steam generated in the heat exchanger 15 will be superheated and this superheat is effective in evaporating the water in the separator and maintaining substantially constant pressure under the demands of the prime mover until the water level in the hot well is again restored and 20 normal feed continued. Steam is also generated in the separator by the evaporation of some of the water therein in response to a reduction of steam pressure.

It is, of course, apparent that the water capacity 25 of the hot well, together with that of the economizer and heat exchanger tubes, and their associated piping up to the separator, should be less than the capacity of the separator so that it will be impossible to flood the separator. 30

The system is essentially free from troubles 35 commonly experienced with other steam generating systems. For instance, damage frequently results in locomotive and other boilers due to an abnormal reduction of water level. With the present system even if the boiler feed water system is allowed to run dry no damage can result. In this case the intermediate fluid pressure will cause the burner to be shut down so that the temperature of the gases in the economizer is not high enough to cause damage to the tubes even if they are empty of water. For the same reasons the superheater tubes can suffer 40 no damage. The heat exchanger tubes can obviously suffer no damage since the temperature 45 of the vapor of the intermediate fluid is held down by reason of the pressure control of the burner. The boiler, per se, cannot run dry since there is no abstraction of the intermediate liquid or its vapor. 50

The accessories of the system, such as the oil burner, the float valve 154, and the pressure valve 170, the oil valve 136, are generally standard pieces of apparatus of proved reliability, operating in their intended manner in the present system and contributing their own reliability to that 55 of the system.

While the pressure of the intermediate fluid vapor is maintained at not greater than a predetermined safe maximum pressure by the automatic 60 operation of the oil burner, a safety valve 178, see Fig. 1, is provided as a precautionary measure.

The heat exchanger tubes 52 are preferably of 65 small cross-section so that if one should burst for some unforeseen reason the volume of steam that can be forced through the ruptured zone into the vapor space of the boiler can amply be taken care of by the safety valve. The exchanger tubes preferably are made of Monel metal which 70 is not subject to pitting. Pitting is largely due to the presence of air in the water in contact with a surface subject to highly heated furnace gases. Since the water is preferably distilled and hence air free and the steam cycle is a closed cycle in 75

which air cannot enter or is removed by the condenser air pump the danger of pitting of any of the tubes is quite remote. Scale deposits, even if present on the inner surfaces of the heat exchanger tubes do not lower the high standard of safety provided by the present system since the tubes are subject only to the temperature of the intermediate vapor and not to the radiant heat of the fire or the highly heated combustion gases thereof which high temperature is the cause of tube failures due to scale deposits.

There is also a substantial absence of pitting of the boiler surfaces in contact with the intermediate fluid and subjected to the radiant heat of the fire and the temperature of the combustion gases by reason of the nature of the intermediate fluid, the characteristics of which prohibit the pitting of the heat transfer surfaces and the fouling thereof by a scale formation which is one of the main operating difficulties of boilers and particularly locomotive boilers.

While the steam pressure is high the actual pressure acting on the boiler structure is very low, being of the order commonly associated with house heating boilers. Hence the structure can be extremely light, not only because of the lower pressure but also because, due to the inertness of the intermediate liquid, no allowance need be made for corrosion.

Due to the location of the combustion chamber entirely within the boiler and practically completely surrounded by the intermediate liquid no heat insulating lining for the combustion chamber is required, which makes the system especially adapted for locomotive use and for use in other localities where the boiler is subject to excessive vibration. Since the fire box is entirely surrounded by the intermediate liquid the radiant heat of the fire is utilized very effectively in heating the liquid so that the boiler has inherently a high power capacity for its volume. The absence of heat insulating linings is also advantageous, in that there is thereby assured a rapid response of the system to load changes, without the generation of uncontrollable excessive intermediate vapor pressures and also without the loss of vapor through safety valves that would otherwise occur upon sudden cessation of steam demand, because of the stored heat in the lining which would be given up to the liquid for an appreciable length of time following the drop of steam flow and reduction of the fire.

The system can supply steam instantly upon demand, without time lag, due to the heat storage capacity of the intermediate liquid, since the vapor pressure of the liquid is automatically maintained substantially constant.

Cessation of steam demand from full capacity operation also results in prompt cessation of steam generation since, due to the generation of steam in the separator, the heat exchanger and economizer are not full of water, as would otherwise be the case, that would be converted into steam after the demand had ceased, which steam would build up excessive pressure that would have to be released through a safety valve.

The Scotch type of boiler also is particularly suited for use with an intermediate liquid, because its large fire box provides for a relatively low rate of heat transfer to the intermediate liquid and thus avoids any tendency toward breakdown of the chemical structure thereof. The large fire box also is advantageous, in combination with the superposed vapor shell, in that the liquid volume is small so that the expense of

filling the boiler with its initial charge of relatively expensive intermediate liquid is kept down.

It is apparent that the construction of the system and of the apparatus thereof and the method of operating the system can be modified largely without departing from the spirit of the invention.

We claim:

1. A unitary intermediate liquid high pressure steam generator comprising a boiler shell having an internal combustion chamber submerged in the intermediate liquid, fire tubes extending from the combustion chamber through the boiler below the intermediate liquid level, water tubes in the vapor space of the boiler above the liquid level, and steam superheater tubes in the fire tubes connected to receive same from the water tubes.

2. A steam generator comprising an intermediate liquid boiler having an internal combustion chamber located in the bottom part of the boiler, fire tubes extending from the combustion chamber through the end of the boiler and disposed above the combustion chamber parallel with the axis of the boiler and distributed in an arcuate line about said combustion chamber, superheater tubes in said fire tubes, a superheater header carried by the end of the boiler, said header being arcuate in correspondence with the arcuate distribution of the fire tubes and being within the arcuate line of said tubes and having superheated and saturated steam chambers connected with said superheater tubes, and water tubes in the vapor space of said boiler having a connection with said saturated steam chamber.

3. A steam generator unit comprising an intermediate liquid boiler having an internal combustion chamber, steam-generating water tubes in the vapor space of said boiler, fire tubes extending from said combustion chamber through an end wall of the boiler, superheater tubes in said fire tubes, a superheater header connected with said superheater tubes and having a connection with said steam-generating water tubes, a combustion gas header in front of said fire tubes, economizer casings located on top of said boiler and extended lengthwise thereof and having communication with said combustion gas header, water tubes in said economizer casings, and means connecting said water tubes with said steam-generating water tubes.

4. A steam generator comprising an intermediate liquid boiler comprising a large lower shell and a small upper shell, said shells having means providing free fluid circulation therebetween throughout the major part of their common length, said lower shell adapted to contain a high boiling point low vapor pressure liquid, and said upper shell adapted to contain the vapor only of said liquid, steam generating tubes located within the upper shell and in contact with the vapor only, and a combustion chamber located internally of said lower shell beneath the liquid level therein.

5. A steam generator comprising an intermediate liquid boiler including a large liquid containing shell containing an internal combustion chamber and adapted to contain a high boiling temperature low vapor pressure liquid, a smaller upper vapor containing shell parallel with said first shell, both shells having registering longitudinally extending openings therein, an apertured tie plate interposed between said shells and secured to both around the openings thereof,

said upper shell providing a vapor chamber for the vapor generated in said lower shell, and steam generating tubes located in said upper shell in contact with the vapor therein.

- 5 6. A steam generator comprising an intermediate liquid boiler including a large liquid containing shell containing an internal combustion chamber and adapted to contain a high boiling temperature low vapor pressure liquid, a smaller upper vapor containing shell parallel with said first shell, both shells having registering longitudinally extended openings therein, an apertured tie plate interposed between said shells and secured to both around the openings thereof, said 10 upper shell providing a vapor chamber for the vapor generated in said lower shell, steam generating tubes located in said upper shell in contact with the vapor therein, fire tubes extending from said combustion chamber through an end 15 wall of said lower shell, superheater tubes in said fire tubes, and a superheater header connected with said superheater tubes.

- 20 7. A steam generating unit comprising an intermediate liquid boiler including a large liquid containing shell containing an internal combustion chamber and adapted to contain a high boiling temperature low vapor pressure liquid, a smaller upper vapor containing shell parallel with said first shell, both shells having registering longitudinally extended openings therein, an apertured tie plate interposed between said shells and secured to both around the openings thereof, said upper shell providing a vapor chamber for the vapor generated in said lower shell, steam generating tubes located in said upper shell in contact with the vapor therein, fire tubes extending from said combustion chamber through an end wall of said lower shell, superheater tubes in said fire tubes, a superheater header carried 25 by said end wall of said shell and connected with said superheater tubes, a combustion gas header located above said superheater header and in communication with said fire tubes, economizer casings extended lengthwise of said shells above 30 said lower shell and on opposite sides of said upper shell and having means establishing communication between them and said combustion gas header, economizer tubes in said casing, and means connecting said economizer, heat exchanger and superheater tubes in series relation.

- 35 8. A steam generating system comprising an intermediate liquid boiler, heating means for the liquid in said boiler, steam generating means in contact with the vapor of said intermediate liquid, means responsive to the pressure of the vapor of said intermediate liquid operable to control the rate of heating of said liquid to maintain a substantially constant vapor pressure irrespective of the rate of steam generation, a steam and water 40 circulating system connected with said steam generating means, and means responsive to the steam pressure operable to regulate the admission of water to a part of said system containing steam to maintain a substantially constant steam pressure.

- 45 9. A steam generating system comprising an intermediate liquid boiler, heating means for the liquid in said boiler, steam generating means in contact with the vapor of said intermediate liquid, means responsive to the pressure of the vapor of said intermediate liquid operable to control the rate of heating of said liquid to maintain a substantially constant vapor pressure irrespective of the rate of steam generation, a steam and water

5 circulating system connected with said steam generating means, and means to maintain a substantially constant steam pressure comprising means responsive to steam pressure to admit water into a steam space of said circulating system.

- 10 10. A steam generating system comprising an intermediate liquid boiler, water-containing steam-generating tubes in the vapor space of said boiler, a closed steam circulating system connected with said tubes, a hot well in said system 10 for the condensate, means for introducing water into said tubes from said hot well, and means responsive to steam pressure in said system to admit water from said hot well into the steam of said steam circulating system when the steam 15 pressure is high, and means responsive to water level in said hot well to admit water into said steam generating tubes when the hot well water level is high.

- 20 11. A closed circuit steam generating system 20 comprising steam generating means, steam condensing means, a steam conduit connecting said means, a hot well in the system between the condensing and the steam generating means, a reservoir for water in said conduit and through 25 which reservoir power generating steam flows between the steam generating means and the condensing means, means for passing water from said hot well into said steam generating means, means responsive to a high level of water in said 30 hot well for admitting water into said steam generating means, and means responsive to a predetermined pressure of steam in said reservoir for admitting water therein from said circulating means to reduce the pressure and to be vaporized 35 and mix with the pressure steam and to produce additional steam.

- 40 12. A steam generating system comprising an intermediate liquid boiler, fuel burning means for heating the liquid in said boiler, steam generating tubes in the vapor space of said boiler, superheater tubes in the combustion gases of said heating means, piping connecting said steam generating tubes and said superheater tubes and including an interposed separator, means for condensing 45 the steam, a hot well receiving the condensate, a boiler feed water means receiving water from said hot well and normally arranged to direct the water into said steam generating tubes, means responsive to the level of water in said hot well 50 for controlling the flow of feed water into said tubes and operable to restrict the flow of feed water when the water level in the hot well is low, and means responsive to steam pressure in said separator for admitting water from said feed 55 water means thereto and operative to admit water when the steam pressure is above a predetermined value.

- 60 13. A boiler having superimposed, parallel, intersecting approximately co-extensive large and small shells opening into each other approximately throughout their lengths, said large shell being approximately filled with a high-boiling-temperature, low-pressure liquid, a combustion chamber surrounded by said liquid, a combustion 65 gas flue leading from said combustion chamber through said liquid, a steam generating tube located in the vapor space of said small boiler shell and heated by the vapor thereof, and a superheater tube connected with said steam generating tube and located in said flue.
